UNITED STATES PATENT OFFICE.

FREDERICK WESTERBECK, OF ST. LOUIS, MISSOURI.

POURING SPOUT FOR LIQUID CONTAINERS.

Application filed May 25, 1925. Serial No. 32,556.

This invention relates generally to improvements in liquid receptacles, and particularly to an improved pouring spout adapted for application to a sheet metal container, such as a can, which is adapted to contain liquid.

Sheet metal containers of the type used to contain oil and other liquids are in most cases provided with simple pouring necks which are not well adapted for use in pouring the liquid from the containers when relatively small streams of liquid are desired. To provide containers with better pouring facilities manufacturers of containers have recently been providing said containers with pouring spouts which are usually attached to the pouring necks of the containers, and are so arranged thereon that they may be moved to an operative position when it is desired to pour liquid from the containers or to an inoperative position when said containers are being packed for shipment.

While many of the pouring spouts heretofore produced functioned in a more or less successful manner, there were certain deficiencies present in connection therewith which prevented said spouts from functioning as desired. For instance, many of the pouring spouts formerly used were so constructed that small bodies of liquid would be trapped in the spout after the container had been righted following a pouring operation, and as a result of this when the person using the container attempted to replace the cover on the pouring neck of said container his fingers would be smeared by these bodies of liquid. Other spouts formerly used were capable of being detached from the pouring necks of the containers, and consequently were frequently lost.

The main object of the present invention, therefore, is to produce a simple and inexpensive pouring spout which is so constructed and arranged that all of the liquid which is in the pouring spout when the container is righted following a pouring operation will immediately drain back into the can, thus maintaining the spout free from liquid. Another object of the invention is to produce a pouring spout which may not be detached from the pouring neck of the container with which it is associated.

With the foregoing and other objects in view, the invention comprises the novel construction, combination and arrangement of parts hereinafter more specifically described

and illustrated in the accompanying drawings, wherein is shown the preferred embodiment of the invention. However, it is to be understood that the invention comprehends changes, variations and modifications which come within the scope of the claims hereunto appended.

Fig. I is a plan view of a can provided with my improved pouring spout, said spout being shown in its inoperative position by full lines and in its operative position by dotted lines.

Fig. II is a fragmentary view, partly in side elevation and partly in vertical section, showing the container and the pouring spout illustrated in Fig. I.

Fig. III is a fragmentary vertical section of a container provided with my improved pouring spout showing said spout in its operative position.

Fig. IV is a section on line IV—IV of Fig. III.

Fig. V is a fragmentary vertical section of a container provided with my improved spout showing the manner of using the cap of the container as a temporary closure for said container when the pouring spout is in its operative position.

Fig. VI illustrates a fragment of the collar portion of my improved spout showing one of the lugs thereon in detail.

In the drawing, A designates a vertical sheet metal receptacle of the type usually employed to contain liquid, said receptacle preferably being provided with a suitable handle B by means of which said receptacle may be conveniently carried. The receptacle A is provided with a pouring neck C which in the drawing is shown as a separate element soldered or otherwise secured to the top wall of the receptacle and extended upwardly from said top wall of said receptacle. The pouring neck C is provided with external screw threads C', and D designates a cap or cover provided with similar screw threads and adapted to screw onto said pouring neck C for the purpose of closing the upper end thereof. By referring to the drawing it will be seen that the pouring neck C is provided with an annular groove 1 at the lower end thereof, and also that said neck is provided with a second annular groove 2 at the upper end thereof. It will also be noted that the pouring neck C is provided with a plurality of vertical grooves 3 spaced equidistant around said pouring

neck and which communicate with said annular grooves 1 and 2.

S designates my improved pouring spout, which comprises a collar portion 5 adapted to surround the pouring neck C of the receptacle A and a lip portion 6 extended outwardly from said collar portion. By referring to Figs. I and IV of the drawing it will be seen that the lip portion 6 of the spout S is provided with convergent side flanges 7 which, together with the bottom wall of said lip portion, convert same into a channel tapering toward its discharge end, whereby liquid discharged into said lip portion will be discharged therefrom in the form of a relatively small stream. Formed on the collar portion 5 of my improved spout S is a plurality of inwardly extending lugs 8 which are intended for a purpose to be hereinafter set forth. The spout S is preferably stamped from a single piece of sheet metal, the collar portion thereof being approximately L-shaped in cross section, as shown in Figs. III and V, said collar portion comprising a vertically arranged annular flange 9 adjacent to the pouring neck of the receptacle and a horizontal flange 10 at the upper end of said vertically arranged flange 9. In the formation of the spout S the lugs 8 are formed by pressing a portion of the vertical flange 9 and stretching a portion of the horizontal flange 10 inwardly, as shown in Fig. VI. In this way lugs are formed which are each provided with oppositely disposed side walls 8^a, a front wall 8^b and a top wall 8^c, and as these walls are all integral with each other a very rigid structure is produced.

The lugs 8 are located on the collar portion 5 of the spout S in the same relation to each other as are the vertical grooves 3 in the wall of the pouring neck C. In other words, when the collar portion 5 of the spout surrounds the pouring neck C the lugs 8 are capable of extending into said grooves 3 and said spout may be moved vertically with relation to said neck, said lugs 8 moving longitudinally of said grooves 3.

When a container provided with my improved spout is in use the collar portion of said spout encircles the pouring neck of the container, and if the spout S be in its inoperative position the lugs 8 extend into the annular groove 1 at the lower end of the pouring neck. When the spout is arranged as suggested, it is plain that said spout may be rotated about the pouring neck C, the lugs 8 moving through said annular groove 1. As already mentioned, when the spout is in its inoperative position the lip portion 6 thereof is located immediately above the top wall of the receptacle, as shown in Figs. I and II, and when said lip portion is so positioned it will not extend beyond the side wall of the container. Assume now that it is desired to move the spout 3 so that the lip por-

tion 6 thereof will be in its operative position; in other words, in the position in which said lip portion is shown in Fig. IV, and with the spout at the upper end of the pouring neck C. In this event the spout S is moved about the pouring neck C until the lugs 8 are in registration with the vertical grooves 3, whereupon said spout may be moved upwardly relative to said pouring neck C, said lugs passing longitudinally through said vertical grooves 3. When the lugs 8 have passed entirely through the vertical grooves 3, said lugs will be located in the upper annular groove 2, whereby said spout S may be moved about the pouring neck C to bring the lip portion of said spout into its operative position where the lugs 8 are offset from the grooves 3, as shown in Fig. IV. The lugs 8 on the collar portion of the spout are of such height that said lugs frictionally grip the upper and lower faces of the annular groove 2 whereby said spout may be retained in any position to which it has been moved.

When the spout is in its operative position it is not possible to screw the cap D onto the pouring neck C of the container, and to provide some means for closing the upper end of the pouring neck I arrange an outwardly extending portion D' on said cap. This portion D' is of such diameter that it will fit into the upper end of the pouring neck C and will frictionally grip the inner face thereof, as shown in Fig. V. By this arrangement a temporary friction cap is provided which may be used without disturbing the position of the spout S.

It will be noted that the pouring neck C of the container is provided with an outwardly extending annular flange 11 at its upper end which acts as a stop for the lugs 8, thus preventing the spout S from being removed from the container.

By referring to Fig. III of the drawing it will be seen that when the pouring spout S is in its operative position any liquid which remains in said spout after the pouring operation will drain back into the receptacle A.

I claim:

1. In combination with a receptacle adapted to contain liquid and having a pouring neck, a pouring spout comprising a member having a collar portion surrounding said pouring neck and a lip portion, means comprising a guideway whereby said pouring spout may be retained in an inoperative position remote from the discharge end of said pouring neck, means comprising a guideway whereby said pouring spout may be retained in an operative position adjacent to said discharge end of said pouring neck, and means comprising guideways arranged longitudinally of said pouring neck and in communication with the first and second mentioned guideways whereby said

pouring spout is permitted to be moved longitudinally of said pouring neck from said inoperative position to said operative position, and portions on said pouring spout 5 adapted to extend into said guideways.

2. In combination with a receptacle adapted to contain liquid and having a pouring neck, a pouring spout comprising a member having a collar portion surrounding said pouring neck and a lip portion, said pouring neck being provided with an annular groove adjacent to the end thereof 10 which is secured to the receptacle whereby said pouring spout may be retained in an inoperative position, said pouring neck being provided with a second annular groove 15

adjacent to the discharge end thereof whereby said pouring spout may be retained in an operative position adjacent to said discharge end of said neck, and said pouring neck 20 being provided with grooves arranged longitudinally of said pouring neck and in communication with said annular grooves whereby said pouring spout is permitted to be moved from said inoperative position to 25 said operative position, and portions on said pouring spout adapted to extend into said grooves.

In testimony that I claim the foregoing I hereunto affix my signature.

FREDERICK WESTERBECK.
